UNITED STATES PATENT OFFICE.

JOHN H. OSBORNE, OF PHILADELPHIA, PENNSYLVANIA, ASSIGNOR TO
LEWIS S. COX, OF SAME PLACE.

METHOD OF CUTTING OUT STOCKING-BLANKS.

SPECIFICATION forming part of Letters Patent No. 242,684, dated June 7, 1881.

Application filed April 4, 1881. (Model.)

To all whom it may concern:

Be it known that I, JOHN H. OSBORNE, a citizen of the United States, residing in Philadelphia, Pennsylvania, have invented certain Improvements in Cutting out Stocking-Blanks, of which the following is a specification.

The object of my invention is to so cut a tube or web of knitted fabric to form stocking-blanks that stockings made from said blanks will be of better shape and more comfortable to wear than cut stockings as made previous to my invention.

In the accompanying drawings, Figure 1 is a diagram showing the method now adopted in cutting tubes of knitted fabric to form stocking-blanks; Fig. 2, a view of part of a stocking made from a blank so cut; Fig. 3, a view showing my improved method of cutting blanks from a tube; Fig. 4, a view of part of a stocking made from a blank cut according to my invention, and Fig. 5 a diagram illustrating the application of my invention to the cutting of stocking-blanks from flat webs instead of tubes.

The ordinary method of cutting tubes of knitted fabric to form stocking-blanks is to form in the tube at intervals a central longitudinal incision, *a*, and two transverse incisions, *b b*, the incision *a* being parallel with the edges of the tube and the transverse incisions *b* extending from the central incision to said edges. (See Fig. 1.) Projections *x* are thus formed on those portions *y* of the tube which form the legs of the stockings, and these projections *x* are then folded on the central line, *x'*, and the edges *d d'* and *e e'* sewed together to form the foot of the stocking, as in Fig. 2. The junction of the two seams is by this method of cutting brought in line with the center of the tube *y*, which forms the leg of the stocking. Hitherto the tubes have been knitted of a size equal to that of the ankle portion of the stocking, and the desired shape of the projecting calf and heel has been imparted by applying the stocking to a press-board or former of the proper outline and then subjecting it to heat and pressure. This stretches the tube of fabric at the calf and heel, and is objectionable, as it interferes with the proper elasticity of the stocking at these points.

A much more acceptable method of making the stocking is to knit the tube in the first instance of a size equal to that of the calf portion of the leg, and impart the proper shape to the ankle and heel by cutting away the rear portion of the tube at *m*, for by this means the stretching of the stocking is prevented and the tube retains its elasticity throughout. This cutting operation, however, removes so much of the rear half of the tube that when the junction of the two seams of the foot is in line with the center of the tube the heel *n* is almost entirely cut away, the shape of the stocking being destroyed, and the comfort of the wearer interfered with.

In order to permit the shaping of the stocking by cutting away the rear portion of the tube, and yet preserve the proper shape of the foot and heel, I discard the usual method of cutting the tube and make the central incision, *a*, at an angle to the edges of the tube, as shown in Fig. 3. By this means the junction of the two seams of the foot is brought considerably in advance of the center line of the tube, and the projection *x* is made much wider at the outer or free end than at the connected end, so that when the stocking is cut and sewed as shown in Fig. 4 the proper shape of the foot and heel is preserved, and the seams are so located as not to interfere with the comfort of the wearer. The stocking in this respect, in fact, is almost or quite as perfect as those known to the trade as "full fashioned" or "full regular made," to which the proper shape is given by the slow and costly process of varying the width of the fabric in the machine during the process of manufacture.

The good shape and perfect fit of the stocking resulting from my improved method of cutting the blank enable me to make a much higher grade of "cut hose" than has hitherto been considered practicable.

My invention may be applied to the cutting of stocking-blanks from flat webs, as in Fig. 5, as well as from tubes, as will be readily understood.

I claim as my invention—

1. The mode herein described of cutting stocking-blanks from tubes or webs, said mode consisting in forming the projecting foot por-

tion *x* with edges inclined in respect to the center line of the tube or web, as set forth.

2. A stocking-blank consisting of a tube or web having a projecting foot portion, *x*, with edges inclined in respect to the center line of the tube or web, as set forth.

3. A stocking made from a tube cut and seamed at *m*, and having the junction of the foot-seams in advance of the center line of the tube, as set forth.

In testimony whereof I have signed my name to this specification in the presence of two subscribing witnesses.

JOHN H. OSBORNE.
